UNITED STATES PATENT OFFICE.

JOHN F. CLASS, OF DAYTON, OHIO.

PROCESS OF GENERATING MINERAL FUMES AND AN APPARATUS FOR GENERATING SAID FUMES.

Application filed December 4, 1919. Serial No. 342,504.

To all whom it may concern:

Be it known that I, JOHN F. CLASS, citizen of the United States, residing at Dayton, in the county of Montgomery and State of 5 Ohio, have invented certain new and useful Processes of Generating Mineral Fumes and an Apparatus for Generating Said Fumes; and I do declare the following to be a full, clear, and exact description of the invention, 10 such as will enable others skilled in the art to which it appertains to make and use the same, reference being had to the accompanying drawings and to the letters and figures of reference marked thereon, which form a part 15 of this specification.

My invention relates to an improved process or method of generating fumes from mineral substances, and applying them to the human body in the treatment of diseases.

20 My invention relates also to the apparatus by means of which the mineralized fumes are conducted to various parts of the body at a known temperature which is essentially below that of the human body to be treated.

25 The process consists primarily in the generation of steam or vapor such as arises from water heated to a point necessary to generate steam; in causing such steam or vapor to pass over shallow bodies of mineral substances consisting of a coal tar product, lime, 30 sulphur, clay and sand.

During the passage of the vapor over said mineral substances, the said vapor becomes impregnated therewith in proportion to the 35 number of mineral bodies over which the vapor passes. Arriving at the last one of the mineral bodies the fumes or mineral laden vapor is of a maximum strength, and of a temperature substantially greater 40 than that of the human body. From this condition the temperature is lowered to a point below that of the particular body to be treated and the strength may or may not be reduced from the maximum strength, according to the particular malady or disease 45 to be treated. To reduce the temperature, the mineralized fumes or vapor is conducted from the generator to one or more reducing chambers provided with temperature recording instruments, whereby the exact temperature 50 is ascertained before it is applied to the body. It is important that the temperature of the mineralized fumes shall be, in every case, below that of the body because of the

fact that the body has a tendency to absorb 55 the fumes or vapor to a greater extent, and because of the further fact that the length of application in many cases requires that the comfort of the patient shall not be interfered with during the treatment. The re- 60 duction of the temperature below that of the body is the last step of the process prior to the application of the mineral-laden fumes or vapor to the body.

A further object of the invention is to provide 65 an apparatus which has been especially designed and constructed for carrying out the process and applying the fumes in the treatment of different diseases. And in which the strength and temperature of the 70 fumes shall be so subject to control that the best results shall follow each application.

The apparatus is illustrated in the accompanying 75 drawings to which reference is made in general terms as follows:—

Fig. 1 is a general view, in elevation, of the apparatus including the vapor or fume generator, the temperature reducer and the several cabinets or inclosures in which the 80 patient is subjected to the fumes at the proper regulated temperature and strength.

Fig. 2 is a front elevation of the generator with the distributing pipes or conduits broken off. Fig. 3 is an enlarged elevation 85 of the generator showing the mineral trays. Fig. 4 is a top plan view of the head-treating cabinet. Fig. 5 is an enlarged side elevation of one of the hoods of the head cabinet, part of the fume chamber being broken 90 away. Fig. 6 is a front view of one of said hoods. Fig. 7 is a bottom plan view of one of said hoods. Fig. 8 is an elevation of one of said hoods with the front removed showing the interior thereof. Fig. 9 is a side elevation of one of said hoods with a side removed to show the interior thereof. Fig. 10 is an enlarged longitudinal top plan view of the lying-down cabinet with a portion of the cover broken away.

100 In a more particular description of the process and the apparatus for carrying out said process, reference in detail is made to the drawings, where like characters will denote corresponding parts.

The generator —1— is located on the lower floor or in the basement of the building in which the apparatus is installed and

the mineral-laden vapor is conducted therefrom to the rooms where the cabinets are located. The generator is shown in Fig. 3 to consist of a lower section —1— and an upper or mineral inclosing section —2— which is supported on and sealed from the lower section —1—. The furnace section or base —3— may be supplied with heat from any source. In the drawings, a gas burner —4— is shown. Above the burner is an evaporating tank —5— supported in the section —1— upon suitable brackets —6—. Water from which the vapor or steam is generated is introduced in said tank —5— by a filler pipe —7— which stands on the outside of the generator. Air and the products of combustion rise in the space —8— around the evaporating tank —5— and together with the steam or vapor from said tank, pass under and above a series of mineral containing trays —9—. The fume producing substances which are placed in these trays may be of any suitable character and may be varied from time to time according to the needs of the patients. Usually they consist in part, at least, of mineral substances and these substances are spread in thin layers in the trays so that they will be acted upon by the warm vapors, or steam, and will give off fumes which will mingle with the vapors as they pass from the generator. The mineral trays —9— are in the upper section —2— of the generator being supported on suitable brackets and spaced one from the other in order to allow a free and ample passage of the vapor as indicated by the several arrows in Fig. 3. Access is had to the mineral trays through a door —10— which forms a portion of the upper section of the generator. Above the generator an initial cooler —11— is supported upon a pipe —12— which extends from the top of the generator and is provided with a damper —13— which controls the passage of the mineral-laden fumes from the generator. A thermometer —14— is located at the initial cooler to indicate the temperature of the fumes therein. A tray —15— is also located in said initial cooler for the reception of any substance that it may be desirable to place therein. A pipe —16— communicates with the initial cooler —11— and with the atmosphere, also with the heat compartment of the generator. The air pipe —16— is controlled by a damper —17— and the passage from the heat compartment to said air pipe is controlled by a damper —18—. If the fumes or vapor in the initial cooler —11— is too strong for a given case, the strength thereof may be reduced by admitting air through the pipe —16— in which case damper —17— is open and damper —18— is closed. Should the temperature of the mineral-laden fumes

in the initial cooler —11— be below the needs of a given case the damper —18— may be open to discharge heat directly to the initial cooler, in which case the air damper —17— is closed. A series of conduits —19— and —21— provided with dampers, and a cap —20—, extend from the initial cooler —11— to the points of application. These conduits convey the mineral-laden fumes to supplemental coolers where the desired temperature is ascertained before the fumes are delivered to the patient. As shown in Fig. 1 the various cabinets for the patients are located on the floor above the generator. They are closely assembled as shown in order to facilitate space, but, it will be understood that each cabinet may be located in an apartment by itself. As shown the mineral-laden fumes are conveyed from the initial cooler —11— through a conduit to the supplemental cooler —22—. From this latter cooler the fumes may be conducted directly to the cabinet and applied to the patient, as in the case of the cabinet —23— where the patient receives it in a sitting position, the fumes being conducted thereto through a damper controlled conduit —24—. The malady from which the patient is suffering and his or her condition determines the selection of the cabinet and the temperature and strength of the fumes, the temperature being ascertained from the thermometer —25— at the cabinet —23—.

Patients in more advanced stages of disease may be treated in lying-down positions, in cabinet —26— from an end of which the head may protrude, through an opening —30'— and rest upon a shelf or rest —31—. The opening —30'— is in the slide —30—. The shelf —31— is adjustable by means of a notched arm —31'—. The slide —30— is raised in guides —34— on the cover to allow the head to rest on the shelf —31— and then is lowered. The cabinet —26— has a further cooler or chamber —27— beneath it into which the mineral-laden fumes are conducted from the supplemental cooler —22— through a conduit —28— controlled by a damper. As shown in Fig. 10 the floor of the cabinet —26— has a number of holes —29— in it through which the fumes escape to the interior of the cabinet. The cover —33— of said lying-down cabinet is attached at one end to the floor thereof by a hinge —34'—, and a thermometer —35— is mounted at a suitable point thereon to ascertain the temperature as applied to the patient. Here, it may be reiterated, that the temperature and strength at which the mineral-laden fumes are administered is important and depend on the character of the disease and the condition of the patient. To the skilled attendant, these requirements are readily discernible;

the temperature being readily known from the temperature indicating devices at various points, and the strength being known ordinarily from the length of time the generator has produced the mineral-ladened fumes.

A special cabinet —36— is provided for the application of the mineral fumes to the head and to this cabinet the fumes are conducted directly through the conduit —19— from the initial cooler —11—. The body of the cabinet —36— forms a supplemental cooler which is provided with a temperature indicating instrument —37—. From the reducing chamber of cabinet —36— the fumes are conducted to a series of hoods —38— which inclose the heads of the patients with the face exposed to the outside air through openings —39— in the front walls of the hoods. The fumes are conducted to these hoods through flexible conduits —40— each of which has a damper —41— from which extends a rope or cord —42— in proximity to the hood where it may be operated by the patient to regulate the supply of fumes to the hoods. The patient sits upon a chair —43— below the hood as shown in Fig. 1. The face openings —39— are lined with suitable soft material —44— such as felt to add to the comfort of the patient, and the opening —45— in the bottom of each hood which incloses the neck is likewise lined with such material. The hood conduits —40— are flexible in order to allow for the vertical adjustments of the hoods to suit different persons or according to their height. For this purpose each hood is provided with slidable guides —46— attached to the back thereof which fit and move in similar guides —47— which are attached to the upper portion of the cabinet body —36—. Each hood is held in the adjusted position by weights —48— shown in Fig. 5 in broken lines. These weights are connected to one end of suitable cables —49— which pass over pulleys —50— on shafts —51— mounted on the sides of the cabinet —36—. The front wall of each hood is hinged at —52— and may be opened to permit the head of the patient to enter. Each hood is provided with a vent —53—, and a thermometer —54— by which the temperature at the hood is ascertainable at all times. The interior of each hood is provided with a suitable yielding head rest —55— in the form of a spring, and a baffle plate —56—, to disperse the fumes entering. The side of each hood is also provided with a hand hole which is normally closed by a cap —57—. Through this opening the hand of the attendant may extend to separate the hair of the patient so that the fumes shall not be obstructed in reaching the scalp.

The operation is as follows: At the beginning of the day, damper —13— is closed, as

is also damper —17— of the air conduit, and damper —18— is opened. When the fumes begin to generate sufficiently and are in proper condition for application, damper —13— is opened and damper —18— partly closed, also damper —17— is partly opened. If the temperature in the initial cooler —11— is above that required, damper —18— is closed and cool air is admitted through damper —17—. As the strength of the fumes becomes less than is desired for a given case, damper —13— may be opened and damper —18— as well as damper —17— closed. To reduce the strength of the fumes and maintain the temperature, damper —13— is closed and dampers —18— and —17— are opened.

By the arrangement of conduits and dampers shown a given strength and a given temperature may be maintained throughout the day or they may be varied as cases may require.

Having described my process of generating and applying mineral-ladened fumes to the human body in the treatment of diseases and the apparatus through the medium of which the process may be carried out, I claim:

1. In an apparatus of the character described, a generator comprising receptacles to contain fume generating substances and means for generating heated vapor and causing the same to circulate over said substances, a conduit to connect said generator with a vapor applying device, and means for taking warm air from said generator in advance of said vapor generating means and delivering the same to said conduit without bringing said air into contact with said fume generating substances.

2. In an apparatus of the character described, a generator comprising receptacles to contain fume generating substances and means for causing heated vapor to circulate over said substances, a conduit to connect said generator with a vapor applying device, and means for delivering air to said conduit from the exterior of said generator.

3. In an apparatus of the character described, a generator comprising receptacles to contain fume generating substances and means for causing heated vapor to circulate over said substances, a conduit to connect said generator with a vapor applying device, and means for delivering air to said conduit either from the exterior of said generator or from said generator at a point below said receptacle.

4. In an apparatus of the character described, a casing, a receptacle supported in said casing and adapted to contain fume generating substances, means for generating heated vapors below said receptacles and causing the same to circulate over said substances, a conduit to connect said casing with

a vapor applying device, and means for taking warm air from said casing at a point below said receptacle and delivering the same to said conduit.

5. In an apparatus of the character described, a casing, a receptacle supported in said casing and adapted to contain fume generating substances, means for generating heated vapors below said receptacles and causing the same to circulate over said substances, a conduit to connect said casing with a vapor applying device, a second conduit leading from said casing at a point below said receptacles to the first mentioned conduit, and separate means to control said conduits.

6. In an apparatus of the character described, a casing, a receptacle supported in said casing and adapted to contain fume generating substances, means for generating heated vapors below said receptacles and causing the same to circulate over said substances, a conduit to connect said casing with a vapor applying device, a second conduit leading from said casing at a point below said receptacles to the first mentioned conduit, means to control the passage of air through said second conduit, and a valve controlled opening connecting said second conduit with the atmosphere.

7. In an apparatus of the character described, a casing having an air inlet and an outlet, a water receptacle arranged above said air inlet, a heater for said receptacle, trays adapted to contain fume generating substances arranged between said water receptacle and said outlet, a conduit to convey fume laden vapors from said outlet to a vapor applying device, and means for supplying warm air from said heater to said conduit without bringing the same into contact with said fume generating substances.

8. In an apparatus of the character described, a casing having an air inlet at the lower portion thereof and an outlet near the top thereof, a water receptacle in the lower portion of said casing, a passageway to conduct air from said inlet to said casing above said water receptacle, a heater for said water receptacle, trays interposed between said water receptacle and said outlet and adapted to contain fume generating substances, a conduit connected with said outlet, a valve to control said connection, a second conduit connected at one end with the first mentioned conduit and connected at its other end with said casing below said trays, and a valve to control said second conduit.

9. In an apparatus of the character described, a casing having an air inlet at the lower portion thereof and an outlet near the top thereof, a water receptacle in the lower portion of said casing, a passageway to conduct air from said inlet to said casing above said water receptacle, a heater for said water

receptacle, trays interposed between said water receptacle and said outlet and adapted to contain fume generating substances, a conduit connected with said outlet, a valve to control said connection, a second conduit connected at one end with the first mentioned conduit and connected at its other end with said casing below said trays, and a valve to control said second conduit, said second conduit having a valve controlled inlet arranged exteriorly of said casing.

10. In an apparatus of the character described, a casing, receptacles arranged within said casing and adapted to contain fume generating substances, means for causing heated vapor to circulate over said substances, a cabinet for applying said vapors to the body, and means for connecting said casing with said cabinet, and means for delivering warm air to said cabinet without passing the same over said receptacles.

11. In an apparatus of the character described, a generator comprising a casing having an inlet at the lower portion thereof and an outlet near the top thereof, a water receptacle in the lower portion of said casing spaced from the wall thereof to form an air passage, a heater for said water receptacle, trays interposed between said water receptacle and said outlet, and adapted to contain fume generating substances, a conduit connected with said outlet, and a valve to control said connection, a second conduit connected at one end with the first mentioned conduit and connected near its other end with the air passageway leading about said water receptacle, and a valve to control said last mentioned connection.

12. In an apparatus for generating medicinal fumes, a generator consisting of two separable sections, one a vapor generator, and the other a fume generator, a cooling reservoir receiving said fumes from the last named generator, and a conduit forming a communication between said cooling reservoir and the atmosphere and the vapor generator respectively; substantially as described.

13. In an apparatus for generating medicinal fumes, a generator comprising two separable sections, one a steam or vapor generator; a series of shallow mineral containers mounted in the other section and in which the steam or vapor volatilizes with said mineral and forms medicinal fumes, a reservoir in which said fumes are discharged for distribution, and a conduit forming a communication between said reservoir and the atmosphere and the steam or vapor generator respectively.

14. In an apparatus for generating medicinal fumes, a mineral fume generator, a reservoir into which the mineral fumes are directly discharged from said generator, distributing conduits extending from said res-

ervoir, a conduit forming a communication between said reservoir and the atmosphere and generator respectively and whereby the strength or the temperature of the fumes in said reservoir may be regulated, and a series of cabinets connected with the distributing conduits of said reservoir.

15. In an apparatus for generating medicinal fumes, a vapor or steam generator, a mineral fume generator, a reservoir receiving the fumes from the last named generator, a conduit forming a communication between

said reservoir and the steam generator and the atmosphere respectively and whereby the strength or temperature of the fumes in said reservoir may be regulated, a supplemental reservoir receiving the fumes from the first named reservoir, a series of hoods supported on the last named reservoir, and conduits connecting said hoods with the last named reservoir.

20 In testimony whereof I affix my signature.

JOHN F. CLASS.
